EX

OR D 14,900

NO. 14,900

MARCH 25, 1884

UNITED STATES PATENT OFFICE.

MERRITT GALLY, OF NEW YORK, N. Y.

DESIGN FOR A CASE FOR MUSICAL INSTRUMENTS.

SPECIFICATION forming part of Design No. 14,900, dated March 25, 1884.

Application filed January 26, 1884. Term of patent 14 years.

To all whom it may concern:

Be it known that I, MERRITT GALLY, residing at New York city, in the county of New York and State of New York, have invented 5 a certain new and original Design for a Case for Musical Instruments or Mantel-Orchestrones, of which the following is a specification, reference being had therein to the accompanying photograph.

10 My design consists, primarily, in the form, and, secondarily, in the ornamentation, of the case for a musical instrument, especially an instrument of the character known as an "orchestrone" or "automatic organ," whereby the instrument becomes a pleasing mantel ornament, and may also serve as an ornamental clock-case.

In the photographic representation of my design, the numeral 1 indicates the body or 20 base of the casing, which is rectangular in general outline and in face view, the ends being perpendicular, and its greatest length in horizontal direction when the instrument is in position for use. The upper and lower corners of this box or casing are surrounded by moldings, as at 2 and 3. The face of casing 1 is ornamented by raised carvings or panels, and in the central portion of more expensive cases I place a clock, as shown at the dial 4. In 25 some of the cheaper cases this dial may be omitted, and its place supplied by a carving or medallion of the same size. The size of the casing is such that it is adapted to rest on a mantel or shelf of usual size. Projecting centrally above the casing 1 is the casing 5, also rectangular in front view, and less in length than the casing 1. The front of casing 5 is ornamented—as by pillars 6 in low relief—and a molding, 7, passes along the front and 30 ends of said casing. At the ends of the casing 5 I place ornamental brackets or scroll-pieces 8, the same extending toward the ends of casing 1. On top of the central casing, 5, I mount a small statuette, 9, which, by preference, should be the statuette of some prominent musical composer.

By this design I produce a casing for a musical instrument which forms a most pleasing

mantel ornament, and, as has been stated, the same may form a highly-ornamental casing for 50 a mantel-clock.

What I claim as new and of my design is—

1. The design for shape or configuration of a case for a mantel musical instrument, consisting of a body or base having a rectangular 55 face, its greatest length in horizontal direction, and a rectangular central projection of less length surmounting the same, substantially as shown.

2. The design for mantel ornament and musical-instrument case, consisting of a base presenting a rectangular face having its greatest length in horizontal direction, and a central dial, and central rectangular projection above said dial, as shown. 60

3. The design for case for mantel-organs, consisting of a base having rectangular face longest in horizontal direction, having bottom and top molding, and central rectangular projection surmounting the same and having top 70 molding, substantially as shown.

4. The design for mantel ornament and casing for musical instrument, consisting of a base having rectangular face in horizontal direction, a rectangular casing of less length surmounting the same, and ornamental pieces 75 88 at each end thereof, substantially as shown.

5. The design for mantel ornament and case for musical instrument, consisting of a base having rectangular face longest in horizontal 80 direction, a rectangular projection surmounting the same, and a statuette surmounting said projection.

6. The design for mantel ornament and musical-instrument case, consisting of a base 85 having rectangular face longest in horizontal direction, a central dial in said face, a rectangular projection surmounting the base over the dial, and a statuette surmounting said projection, all substantially as shown.

In testimony whereof I affix my signature in presence of two witnesses.

MERRITT GALLY.

Witnesses:

FRANK P. GILLESPIE,
D. B. GALLY.
